UNITED STATES PATENT OFFICE.

JAMES J. LESSLIE, OF BOSTON, MASSACHUSETTS.

Diestock.

Application filed August 15, 1921. Serial No. 492,300.

To all whom it may concern:

Be it known that I, JAMES J. LESSLIE, a subject of the King of Great Britain, residing at Boston, in the county of Suffolk and State of Massachusetts, have invented new and useful Improvements in Diestocks, of which the following is a specification.

This invention relates to an appliance for cutting external screw threads on the ends 10 of lengths of metal pipe, the appliance including a stock formed to receive and rotate either of a plurality of interchangeable thread-cutting dies about a fixed pipe length, and hold the thread-cutting means of the 15 die coaxial with the stock, and a bushing located at one side of the stock, and adapted to be supported by a portion of the fixed pipe during the cutting operation, to provide an elongated bearing of the appliance 20 on the pipe.

The object of the invention is to provide a one-piece multiple bushing for an appliance of this character, having a plurality of bores or orifices adapted to cooperate with 25 pipes of different diameters, the bushing being permanently and movably connected with the stock, and adapted to be displaced, to permit the interchange of dies, and secured with either of its orifices in axial alignment with the stock.

The invention is embodied in the improvements which I will now proceed to describe and claim.

Of the accompanying drawings forming a 35 part of this specification.—

Figure 1 is a side elevation of a combined stock and bushing embodying the invention.

Figure 2 is a section on line 2—2 of Figure 1.

Figure 3 is a fragmentary perspective view, showing a portion of the die-confining holder hereinafter described.

Figure 4 is a perspective view of the clamping ear which secures the holder in its 45 operative position.

Figure 5 is a side view of the stock body.

Figure 6 is a side view of a screw-cutting die.

Figure 7 is a side view of the die-confining holder.

Figures 5, 6 and 7 are on a much reduced scale.

The same reference characters indicate the same parts in all of the figures.

55 The die-stock body shown by Figures 1,

2 and 5, may be of any suitable form and construction, providing a hub portion having a polygonal socket or cavity 12 for the reception of an externally polygonal standard die 13, said socket enabling the stock 60 to engage and rotate the die on a fixed pipe length constituting the axis of the stock, and oppositely projecting socketed arms 14, adapted to receive the usual elongated handles whereby the stock body and a die therein may be manually rotated about a pipe 65 length 15, the latter being held by a vise, and its threaded end being within the cavity 12 at the conclusion of the thread-cutting operation, as shown by dotted lines in Figure 70 2.

16 represents a die-confining holder, displaceably connected with the stock-body, so that it may be displaced from its operative position to permit the insertion and removal 75 of the die, a different die being required for each size of pipe. The holder 16 is preferably provided at one end with an ear 17, pivoted by a screw 18 to one end portion of the stock body, and adapted to be swung 80 edgewise to cover and expose the die cavity.

19 represents a multiple bushing which is rotatable on and displaceable with the holder 16, and is provided with a plurality of pipe-receiving orifices 20 of different 85 diameters, which are offset from the stock and from the holder so that the wall of an orifice receiving a pipe 15 is spaced outwardly from the stock and the die therein, the bushing being preferably hollow and provided 90 with a rim or flange 19^a, projecting from its inner side and bearing on the holder 16, as shown by Figure 2. The holder is provided with an orifice 22 of greater diameter than the largest pipe, and arranged to be coaxial 95 with the stock when the holder is in its operative position, so that the pipe may project through the holder.

The arrangement of the orifices 20 and of the means rotatably connecting the bushing 100 with the holder is such that when the holder is in its operative position, either orifice 20 may be located in axial alinement with the stock. I prefer to rotatably connect the bushing with the holder 16, by a stud 24, 105 fixed to the holder and eccentric to the axis of the stock, said stud entering a central socket 25 (Figure 2) in the bushing. The stud is threaded and provided with a clamping nut 26, adapted to clamp the bushing 110.

against the holder. The centers of the orifices 20 are concentric with the stud 24, as indicated by the dotted circle 27 (Figure 1).

To releasably secure the holder 16 in its operative position, I provide the swinging end of said holder with a notch 28, with which is interlocked an angular shoulder 29, on a clamping-ear 30. Said ear has an orifice 31, receiving a headed clamping screw 32 engaged with the stock body. The ear 30 has a lip 33 which bears on the outer side of the holder 16 when the screw is tightened. Turning of the clamping-ear on the screw is prevented by ribs 35 on the stock body.

15 The bushing 19 is releasably secured to the holder 16 in either of a plurality of positions, in each of which one of the orifices 20 is in axial alinement with the stock. Means to this end is preferably embodied in a plurality of salient angles on the perimeter of the bushing formed, as here shown, by imparting a hexagonal form to said perimeter, and in a boss 38, formed on the holder 16, and having a reentrant angled recess 39, 25 adapted to receive either of the said salient angles, the latter corresponding in number and position with the orifices 20, as shown by Figure 1.

Before inserting a die 13 in the stock 30 cavity 12, the holder 16 is released and displaced with the bushing. The die is then inserted and the holder is replaced. The bushing may be adjusted to bring either of its orifices into axial alinement with the stock by loosening the clamping-nut 26, 35 moving the bushing outward, turning it to enable either of its salient angles to enter the recessed boss 38, and finally tightening the nut 26. The thread-cutting operation 40 may now be performed as usual.

I claim:

1. A thread-cutting appliance comprising, in combination, a die stock including a hub portion having a socket adapted to receive 45 and rotate a standard die on a pipe length constituting the axis of the stock, a stud, means securing the stud to the stock in a position eccentric to the axis of the latter, a multiple bushing rotatable on said stud, 50 and provided with a plurality of pipe-receiving orifices of different diameters, the arrangement being such that either orifice may be located coaxial with the stock by a rotary movement of the bushing, and means 55 for securing the bushing to the stock in either of a plurality of operative positions.

2. A thread-cutting appliance comprising, in combination, a die stock including a hub portion having a socket adapted to receive 60 and rotate a standard die on a pipe length constituting the axis of the stock, a stud, means securing the stud to the stock in a

position eccentric to the axis of the latter, a multiple bushing rotatable on said stud, 65 and provided with a plurality of pipe-receiving orifices of different diameters, the arrangement being such that either orifice may be located coaxial with the stock by a rotary movement of the bushing, and means 70 for securing the bushing to the stock in either of a plurality of operative positions, means being provided for permitting the displacement of the said stud with the bushing to permit the insertion and removal of a die. 75

3. A thread-cutting appliance comprising, in combination, a die stock including a body adapted to receive and rotate a thread-cutting die, and a holder pivoted to the body and adapted to confine a die therein, the holder being displaceable from its operative position; means for releasably confining the holder in its operative position, a multiple bushing connected with the holder to rotate on an axis eccentric to the axis of the stock, 80 and provided with a plurality of orifices of different diameters, the arrangement being such that either orifice may be located coaxial with the axis of the stock by a rotary movement of the bushing, and means for securing the bushing to the holder in either of a plurality of operative positions.

4. A thread-cutting appliance substantially as specified by claim 3, the said holder being adapted to swing edgewise from one 95 end to and from its operative position, and provided with a stud eccentric to the axis of the stock; the stock body and the swinging end being provided with means for releasably confining the holder in its operative 100 position, and the bushing being rotatable on said stud.

5. A thread-cutting appliance substantially as specified by claim 3, the said holder being adapted to swing edgewise from one 105 end to and from its operative position, and provided with a stud eccentric to the axis of the stock, and with a notch in its swinging end, the said appliance including also a clamping ear having an angular shoulder 110 adapted to engage said notch, and a clamping-screw connecting said ear with the stock body, the bushing being rotatable on said stud.

6. A thread-cutting appliance substantially as specified by claim 3, the bushing being provided with a plurality of salient angles, and means for securing the bushing to the holder, including a recessed boss on the holder adapted to engage either of 115 said angles and a clamping-nut on said stud.

In testimony whereof I have affixed my signature.

JAMES J. LESSLIE.
